(57) **CLAIM**

The ornamental design for a cable connector for nuclear source carrier, as shown and described.

DESCRIPTION

FIG. 1 is a front perspective view of a cable connector for nuclear source carrier according to the claimed design.

FIG. 2 is a front view, the rear view being and or mirror image thereof;

FIG. 3 is a left side view thereof;

FIG. 4 is a right side view thereof;

FIG. 5 is a top view thereof;

FIG. 6 is bottom view thereof;

FIG. 7 is a disassembled front perspective view of the connector (for the sealed carrier) shown in FIG. 1.

FIG. 8 is a disassembled front view of the connector shown in FIG. 7;

FIG. 9 is a disassembled top view thereof;

FIG. 10 is a front perspective view according to the claimed design;

FIG. 11 is a front view of the connector shown in FIG. 10, with the rear view being a mirror image thereof;

FIG. 12 is a top view thereof;

FIG. 13 is a cross-sectional view taken along line 13-13 from FIG. 12; and,

FIG. 14 is a disassembled front view according to the claimed design.

The dash-dash broken lines in the drawings show environmental subject matter and form no part of the claimed design.

The dot-dash broken lines of FIGS. 7-8 show directional arrows of the invention in a disassembled state and form no part of the claimed design.

The dot-dash broken lines of FIG. 10 define the bounds of the claimed design and form no part thereof.

1 Claim, 5 Drawing Sheets
